DESIGN FOR A FLUORESCENT TABLE LAMP

Carl Edward Swanson, Chicago, Ill.

Application August 4, 1941, Serial No. 102,673

Term of patent 14 years

To all whom it may concern:

Be it known that I, Carl Edward Swanson, a citizen of the United States and residing in Chicago, in the county of Cook and State of Illinois, have invented a new, original, and ornamental Design for a Fluorescent Table Lamp, of which the following is the specification, reference being had to the accompanying drawing, forming a part thereof.

On the drawing:

Fig. 1 is a side elevation of my new design of fluorescent table lamp, the shade being removed.

Fig. 2 is a cross-sectional view thereof taken on a plane indicated by line II--II of Fig. 1.

I claim:

The ornamental design for a fluorescent table lamp, substantially as shown.

CARL EDWARD SWANSON.
